UNITED STATES PATENT OFFICE.

WILLIAM S. WARD, OF PLANTSVILLE, CONNECTICUT, ASSIGNOR TO
H. D. SMITH & CO., OF SAME PLACE.

DESIGN FOR CARRIAGE-SHACKLES.

SPECIFICATION forming part of Design No. 11,641, dated February 3, 1880.
Application filed July 19, 1879. Term of patent 14 years.

To all whom it may concern:

Be it known that I, WILLIAM S. WARD, of Plantsville, in the county of Hartford and State of Connecticut, have invented a new 5 Design for Carriage-Shackles; and I do hereby declare the following, when taken in connection with the accompanying drawing and the letters of reference marked thereon, to be a full, clear, and exact description of the same, 10 and which said drawing constitutes part of this specification, and represents a perspective view.

This invention relates to a design for carriage-shackle, the object being the ornamentation of the coupling to which the thill-iron 15 is attached; and the invention consists in the shape of the ears of the coupling, as shown in the accompanying illustration.

A represents the clip, on which are formed 20 the two ears B B, distant from each other, so

as to receive the shaft-eye between them. The outer ends of these ears are semicircular, and on the outside of each ear is a circular projection, a, corresponding to the semicircular end of the ears, and showing on the front a thickness equal to the thickness of the ear and projection combined, but forming a shoulder on the ear at the rear of the projection, the circular projection being concentric with the bolt-hole through the ears, as shown. 25

I claim—

The design for thill-coupling, consisting in the circular projection a on the outside of and flush with the forward semicircular end of the ears, as shown in the accompanying illustration. 35

W. S. WARD.
